(57) CLAIM

I claim the ornamental design for a gripping label holder, as shown and described.

DESCRIPTION

FIG. 1 is a perspective view, taken from the front and right, of a gripping label holder of the present invention;

FIG. 2 is a perspective view, taken from the rear and left, of the label holder shown in FIG. 1;

FIG. 3 is a top view of the label holder shown in FIG. 1;

FIG. 4 is a front view of the label holder shown in FIG. 1;

FIG. 5 is a bottom view of the label holder shown in FIG. 1;

FIG. 6 is a side view, taken from the left, of the label holder shown in FIG. 1;

FIG. 7 is a side view, taken from the right, of the label holder shown in FIG. 1;

FIG. 8 is a right front perspective view of a second embodiment of the gripping label holder of FIGS. 1-7, the sole difference being that all surfaces are opaque except the front panel, which is transparent; and,

FIG. 9 is a left rear perspective view thereof.
